UNITED STATES PATENT OFFICE.

OCTAVIO PIMENTA, OF CARDENAS, CUBA.

SUGAR-PACKING MACHINE.

SPECIFICATION forming part of Letters Patent No. 427,107, dated May 6, 1890.

Application filed October 6, 1886. Serial No. 215,480. (No model.)

To all whom it may concern:

Be it known that I, OCTAVIO PIMENTA, of the city of Cardenas, in the Island of Cuba, have invented certain new and useful Improvements in Sugar-Packaging Machines; and I do hereby declare that the following is a full, clear, and exact description thereof, reference being had to the accompanying drawings, in which—

10 Figure 1 shows a perspective view of my machine or apparatus ready for use; Fig. 2, a detail perspective view showing the receiving and holding box or casing raised and partly filled; Fig. 3, a vertical sectional view on line $\alpha\alpha$ of Fig. 2; Fig. 4, a detail bottom perspective view of the sliding supporting-plate; Fig. 5, a detail perspective view showing the cube-receiving or mold-plate with the cubes as delivered thereto; Fig. 6, a similar view showing the method of closing up or compacting the layer of cubes on the plate, and Fig. 7 a similar view of the tool or device used for so compacting the layer.

In the drawings like letters designate like parts in all the figures.

The object of my invention is to provide an improved method of and apparatus for packing cubes or blocks of sugar; and to this end my invention consists in the method and in the apparatus, and the construction, arrangement, and combination of parts, as hereinafter specified.

Where the cubes or blocks of refined sugar are poured or turned into barrels or boxes, they cannot be packed tightly therein. They will be or become loose in the package, and, being shaken or jarred in transportation, will be much injured by grinding or rubbing against each other. By this grinding or rubbing not only is the shape of the cubes destroyed, but a considerable amount of the sugar is broken up and made into dust or powder, which is to a considerable degree a waste.

By my method and machine or apparatus, as hereinafter specified and shown in the drawings, the blocks or cubes can be packed rapidly, accurately, and closely in one large solid mass, so that they cannot shake around and rub against or grind each other, as when packed in barrels or cases, as the packing has been done heretofore.

In the drawings, A designates the main table of my machine, having an extension A' at each side of its front end, so that the whole 55 table is T-shaped in plan view. I have shown this table as supported by a number of legs a ; but do not limit myself to such construction.

The outer and rear sides of the arms or extensions A' A' of the table, which are rectangular in form, are provided with the raised rims a' a' , preferably of a height equal to or about the height or thickness of the cubes or blocks of sugar. The raised rim on each of 65 the table-extensions extends around and parallel to the outer and rear sides of the extension, thus forming two contiguous sides of a square.

In the main portion of the table is a square 70 opening B, and fitting and sliding up through such opening is the box C, having its sides at least preferably made of sheet metal. Two contiguous sides C' C' of this box are, as shown, extended up above the plane of the 75 tops of the other sides a distance equal to or about the height of the blocks of sugar to be packed. The sides so raised above the others are the rear and right-hand sides, but, if desired, or found convenient, can be the rear 80 and left sides instead.

Within the opening B in the table is a small table D, corresponding in shape with but smaller than the opening, so as to leave sufficient space around it between its sides 85 and those of the opening for the passage of the sides of the box C, already described. This small table D is supported or held in place by the four legs d d , extending down within the box C and through its bottom C². 90 Said bottom is at its four corners provided with the openings c, allowing the passage of and fitting the table-legs d d , so as to guide the box C steadily in its up and down movements.

To raise and lower the box C, I have fixed to its bottom the nut E, up through which extends the vertical screw F, journaled at its lower end in a suitable support or step F'. Rigidly connected with this screw is the 100 bevel-gear G, meshing with and driven by the bevel-gear G' on the shaft G², journaled in suitable bearings, as shown. Upon the forward end of this shaft is another bevel-gear

G^3 , meshing with and driven by the corresponding gear G^4 on the vertical shaft G^5 , which at its upper end is provided with the crank-wheel G^6 , as shown, by which the shaft 5 can be turned in either direction, as desired, to cause the screw F to raise or lower box C .

The small table D is provided with two parallel rearwardly-extending grooves $d' d'$, within which are journaled rollers $d^2 d^2$. In 10 the main table there are similar grooves, forming rearward extensions of those in table D , and similarly provided with rollers.

A plate H , of the same size as table D and provided on its under side with the ribs or cleats $h h$ to fit in the grooves $d' d'$ and rest on the rollers $d^2 d^2$, is placed on the table to receive and support the mass of sugar inclosed by box C during the process of packing. When this box has been lowered below 20 the table, this plate can be slid rearward off the table D onto the main table, carrying any load of sugar that may be upon it.

In the main table between the rollered grooves is a depression or opening I , for a 25 purpose to be described hereinafter.

In Figs. 6 and 7 I have shown the means which I employ for compacting the layer of blocks or cubes on plate K , so that said layer will fit within and can be inclosed by the 30 sides of box C when it has been transferred to the table D .

The device which engages and presses the two contiguous sides of the layer of cubes is formed of two bars or sticks of wood L and 35 L' , connected together by means of a portion l of the bar L passing through a slot l' in bar L' .

In using my apparatus or machine in accordance with my process or method the carrier-plate K , which I term the "mold-plate," 40 having the cubes or blocks of refined sugar situated thereon, as shown in Fig. 5, just as they are delivered to it by the machine which forms the cubes, is placed upon the extension A' of the machine-table, as indicated in Fig. 45 6. Two of the sides of the layer of cubes on the plate will then be engaged by the two raised rims $a' a'$ on the table at right angles to each other. The connected bars $L L'$ are 50 then held at right angles to each other and parallel to the two rims $a' a'$, respectively, and are forced against the sides of the layer of blocks opposite to those engaged by the rims $a' a'$. The blocks will thus be moved 55 up together, as shown in Fig. 6, into a compact rectangular layer. The plate carrying this compacted layer and the two bars $L L'$ is then transferred to the sliding plate H , resting on table D . The box C has previously 60 been adjusted by the screw, so that its two lower sides are flush with the table and its two higher sides stand above the same, as shown in Fig. 1. The layer of blocks of sugar is then transferred to plate H by holding the 65 bars $L L'$ still and drawing out plate K . By turning the wheel G^6 the screw F is then

caused to raise the box C up, so that its two lower sides are flush with the layer of sugar on plate H , and its higher sides stand above the same. Another layer of blocks on a mold-plate is then compacted, as before, and transferred to the top of the layer already in box C , just as the first layer was deposited on the plate H . The box C is then raised again to inclose this new layer also, and so the operation goes on until a sufficient number of layers has been compacted and inclosed by box C to make a mass large enough to fill the box or case in which the sugar is to be packed. Such packing box or case is then inverted and 70 placed down over the box C , with its inclosed mass of sugar. The screw F is then turned to carry the forming and holding box C down below the table A . The car or sliding plate H is then slid rearward on the main table until 75 over the depression or opening. The hand can then be placed under the plate H , and the box inclosing the sugar can be inverted, the plate being held in place thereon, so as to prevent the sugar falling out. The plate being then removed, the cover of the box can be nailed on.

If desired, the forming and holding box or casing C can be lowered before the packing-box is placed over the mass of blocks on plate 95 H , instead of placing the packing-box over the sugar and the box C together. The walls of box C are, however, being made of sheet metal, so thin as to take up very little space between the sides of the mass of sugar blocks 100 and of the packing-box if box C should not be lowered before putting the packing-box down in place.

Obviously my machine or apparatus can be used for packing blocks or pieces of other 105 materials besides sugar where it is desired to have said blocks or pieces closely packed in layers.

Without departure from my invention my machine can easily be adapted for packing 110 bodies of other forms than cubical and for packing them in other than cubical or rectangular boxes or cases. If, for instance, it should be desired to pack round or spherical bodies in layers in square or other boxes, it 115 can obviously be done easily and accurately by means of my machine, layer after layer being successively put in place within the receiving and holding casing C , and transferred therefrom without disturbance by placing the 120 packing-box over casing C , withdrawing the latter, and then inverting, as described hereinbefore. If desired, the rim $a' a'$ at the left side of the table can of course be used, and the left-hand side of box or casing C can be 125 raised instead of the right-hand one, as shown in the drawings. The bars L and L' are preferably made rectangular in shape with straight parallel sides, and the ends of the slot l' are likewise made straight and parallel 130 and at right angles to the sides of bar L' . At the ends of the reduced portion l of bar L

there are shoulders which are at right angles to the sides of the bar. With this construction the bars L and L' can obviously be easily maintained exactly at right angles to each other while employed to compact the layer, as described.

Having thus described my invention, what I claim is—

1. In a machine for packing bodies in layers, the combination, with the plate for receiving the bodies, of a stationary rim adapted to engage contiguous sides of the plate and the layer of bodies thereon, and a movable device adapted to engage the layer of bodies on the plate on the sides not engaged by the said rim, substantially as and for the purpose specified.

2. In a machine for packing bodies in layers, the combination, with the movable plate for receiving the bodies, of the table provided with the raised rim a' a', adapted to partially inclose the plate and the layer thereon by engaging the contiguous sides of the plate and layer, and the movable device adapted to engage the other sides of the layer and make with the rim a' a' a complete inclosure of the same, substantially as and for the purpose shown.

3. In a machine for packing, in combination with a suitable table having an opening of the shape of the packing-box to be used, a table or support within such opening, and the receiving and holding box moving up through the opening around such support, substantially as and for the purpose shown.

4. In combination with the receiving and holding box, the stationary table or support entirely inclosed by the same, and means for moving the box up and down with relation to the table, substantially as and for the purpose described.

5. In combination with the movable box or casing having portions of its walls higher than others, the stationary support inclosed by the box, and means for moving the box up or down, substantially as and for the purpose described.

6. In combination with the rectangular box or casing having two contiguous sides higher than the other two, the stationary table or support within the box, substantially as and for the purpose described.

7. In combination with the stationary table or support and the movable box or casing inclosing the same, the movable plate resting on such support and adapted to be inclosed by the casing as it rises, substantially as and for the purpose described.

8. In combination with the movable receiving and holding casing, the grooved stationary support within the same, provided with rollers in the grooves, and the plate provided with ribs to engage such grooves and rollers, substantially as and for the purpose described.

9. In combination with the table having the opening shaped to correspond with the packing-casing to be used, the movable receiving

and holding casing fitting and adapted to be moved up and down through the opening, the stationary support within such opening, inclosed by the movable casing as it rises, and means, substantially as described, for raising and lowering the casing.

10. In combination with a table having a suitable rectangular opening, the small table within such opening of such size as to leave a space between its sides and those of the opening, the rectangular box adapted to be moved up and down with its sides inclosing such small table, and having two of its contiguous sides higher than the others, substantially as and for the purpose described.

11. In combination with the table having the rectangular opening, the movable casing fitting and moving through such opening, having two contiguous sides higher than the others, the stationary smaller table within the opening, the carriage-plate resting on this table and inclosed by the casing as the latter rises, and means for raising and lowering the casing, substantially as and for the purpose described.

12. In combination with the main table having the rectangular opening and the grooves extending therefrom provided with rollers, the smaller table within said opening, also provided with rollered grooves, and the plate having ribs on its lower side to fit the grooves, substantially as and for the purpose described.

13. In combination with the stationary support or small table, the casing adapted to inclose the same, a nut on the bottom of the casing, the screw, and means for turning the latter, substantially as and for the purpose described.

14. As a means for moving the blocks together into a compact rectangular layer, the fixed rims adapted to engage two contiguous sides of the layer, and the two bars joined together so as to be capable of sliding one upon the other and made longer than the corresponding opposite rims, substantially as and for the purpose described.

15. The process of packing bodies in layers, which consists in first compacting each layer, then placing the same on a support, then moving a holding-casing up to inclose the layer, then compacting the subsequent layers, placing them successively on the preceding ones and raising the casing up around them as they are put in place, and finally setting the packing-box down over the mass, substantially as and for the purpose described.

16. The process of packing bodies, which consists in placing them layer upon layer on a suitable supporting-plate, raising a casing up to inclose each layer as it is put in place, inclosing the whole mass, with the packing-box inverted, withdrawing the holding-casing, turning the packing-box over with the plate held against it, and finally closing the box-top, substantially as and for the purpose described.

17. The method of preparing bodies in lay-

ers to be inclosed by a packing-box, which consists in compacting the bodies in layers, placing these layers one upon the other on a suitable support, and raising an inclosing-casing up around the layers as they are successively put in place, substantially as and for the purpose described.

In testimony that I claim the foregoing I have hereunto set my hand this 16th day of September, 1886.

OCTAVIO PIMENTA.
